BROODER

Karl W. Casey, Casey, Wash.

Application May 28, 1930. Serial No. 456,560

2 Claims. (Cl. 119—34)

This invention relates to certain new and useful improvements for brooder devices of the type used for small chicks.

A primary object of this invention is to provide a brooder device of the above-mentioned character, adapted to accommodate a large number of chicks, without crowding, or causing discomfort to the chicks.

A still further object of the invention is to provide a brooder device accommodating a maximum number of chicks in a minimum amount of space.

A still further object of the invention is to provide a brooder device which at all times may be kept at a desired temperature, and further to provide a brooder device having suitable means for providing for a continuous circulation of fresh warm air under pressure, the warm air entering the compartments of the brooder device from the top thereof and deflected downwardly to be equally distributed in all directions.

A still further object of the invention is to provide a brooder device wherein fresh air can be directed toward the chicks in the brooder device in such a manner that the chicks may seek a temperature comfortable to them by going closer to or farther from the point where the air is released.

Other objects and advantages of the invention will become apparent during a study of the following description, taken in connection with the drawings, wherein:

Figure 1 is a fragmentary view partly in elevation and partly in vertical section showing the brooder chambers and the means for supplying heated air thereto the section being taken on line 1—1 of Figure 2.

Fig. 1a is a plan view partly in horizontal section showing the means for heating the air and for forcing it to the brooder chambers.

Fig. 2 is a section on line 2—2 of Figure 1.

Fig. 3 is an elevational view of the lower end portion of the housing.

With reference more in detail to the drawings, it will be seen that my invention comprises a vertical housing 7 mounted on suitable supporting legs 6. The housing 7 is preferably of rectangular configuration in cross section, and is made from wire mesh screen.

Arranged in the housing 7 is a plurality of vertically spaced horizontal partitions 5 dividing the housing into a plurality of compartments 8 for accommodating the chicks. The partitions 5 are provided with flanges on opposite sides

thereof suitably secured to the frame work 7' of the housing 7.

Each compartment 8 is provided with a bottom 9 formed preferably of wire mesh and disposed above and in spaced relation to the adjacent partition 5.

The partitions 5 slidably support thereon a plurality of sliding trays 13, the trays being slideable on the partitions between the flanges of the partitions and a pair of spaced parallel guide members 12 to facilitate the removal and replacing of the trays individually.

Obviously, any refuse in the compartment will fall by gravity into the trays 13 or may be swept into the trays, after which the trays may be withdrawn for emptying, thus facilitating the cleaning of the compartment.

Arranged in each compartment 8 and depending from the adjacent partition 5 forming the top of the compartment, are circular curtains 14, the curtains 14 terminating slightly above the bottoms 9 of the compartments. The curtains 14 are preferably wool, such being commonly used in brooders.

For each compartment 9, there is provided a trough 15 extending along all four sides of the housing 7 slightly above the partition 5, the bottom of the trough 15 being substantially in the plane with the bottom 9 of the compartment. Obviously, food, water and the like may be placed 85 in the troughs for the convenience of the chicks in the respective compartments.

Thus, it will be seen that the brooder device is comparatively simple in construction, the compartments of the housing being so arranged as 90 to provide a comfortable housing for the chicks.

As comprehended by the present invention, each compartment has warm fresh air supplied thereto for maintaining the compartment at a desired and proper temperature.

To this end, there is provided a casing C arranged exteriorly of the brooder room A. Arranged within the casing C are heating coils 16.

The ends of the coils 16 are in communication with a boiler B arranged adjacent the casing C, through the medium of pipes 17 and 18 respectively, the pipe 17 having a branch 19 leading therefrom to the boiler B. The pipe 17 is also connected to a water supply tank T disposed in proximity to the boiler B. The casing C is provided with a suitable air intake pipe 20 controlled by a suitable valve or damper 21, so that obviously, air circulating within the casing C will be heated by contact with the coils 16.

A hot air inlet 22 leads from the casing C to 110

a suitable blower 23. A warm air conduit pipe 24, leads from the outlet of the blower 23. The conduit pipe 23 leads under the housing 7, and is arranged in a substantially rectangular frame-like manner, in the brooder room A and terminates in a reduced return pipe 25 leading into the casing C through one side of the casing.

Arranged in the return pipe 25 is a suitable valve or damper 26, which is adapted to be manually operated.

Leading from the hot air conduit 24 is a branch 27. Leading laterally from the branch 27 are a plurality of outlet pipes or branches 28, there being one outlet pipe or branch 28 for each compartment 8.

Thus it will be seen that the outlet branches 28 lead through one side wall of the housing 7 into the compartments 8 at the top of the compartments, to terminate at their inner ends within the confines of the curtains 14.

At its inner end, each outlet branch pipe 28 is provided with a discharge opening 29, whereby the heated air passing through the outlet branch 28 is directed downwardly of the compartment.

Each of the outlet branch pipes 28 exteriorly of the housing 7 is provided with a control damper or valve 30.

It may be well to mention, that two or more brooder devices may be used with this type of heating system, and to this end as suggested in Fig. 1 additional outlet branches 28 may be provided for distributing heat to the compartments of additional brooder devices.

To insure equal distribution of the heated air to each of the compartments, there is arranged in each compartment, a conical deflector 31. The conical deflector is arranged with its largest portion resting approximately on the wire bottom 9, the apex of the conical deflector being in substantially vertical alignment with the outlet opening 29, so that obviously as the heated air is discharged from the opening 29, the air will impinge against the deflector 31 and thus be equally distributed to all parts of the compartment.

Thus it will be seen that at all times, there is provided a circulation of heated air for maintaining the brooder compartments at a desired temperature.

It may be also noted from a study of Figs. 1 and 1a, that leading to the casing C, is an air inlet pipe 32 leading from the brooder room A in which the brooders may be arranged. A suit-

able control damper or valve 33 is arranged within the air inlet pipe 32.

Access to the compartments 8 may be had from two sides of the housing 7 thru suitable openings arranged in opposite side walls of the housing. The openings are normally closed through the medium of suitably hinged doors 11 having suitable latch means 12 associated therewith for normally retaining the doors in closed position.

The doors 11 may be of any desirable structure, but preferably consist of a suitable frame in which is mounted suitable wire mesh.

It is thought that from the foregoing description, taken in connection with the accompanying drawings, a clear understanding of the construction, advantages and arrangement of parts of a brooder device of this character will be had by those skilled in the art without a more detailed description.

Even though I have herein shown and described the preferred embodiment of my invention it is to be understood that the same is susceptible to changes fully comprehended by the spirit of the invention as hereinafter described, and the scope of the appended claims.

Having thus described my invention, what I claim as new is:—

1. A brooder room having a chamber therein, a pipe extending into said chamber and having at its inner end an air discharge opening, an annular curtain depending from a wall of said chamber circumjacent the discharge opening, a conical deflector supported in the bottom of the brooder chamber and having its apex substantially in alignment with the discharge opening 105 of said air pipe and means for introducing hot air into said pipe.

2. In a brooder, a chamber including a bottom, a perforated false bottom located in spaced relation above the first-mentioned bottom, a curtain depending from the top of the chamber and having its lower end spaced from the false bottom, a hot air pipe extending into the upper part of the chamber and having an end terminating in the space formed by the curtain, said end having an opening in its lower portion for directing the heated air from the pipe downwardly and a cone resting on the false bottom with its apex under the opening in the pipe, said curtain forming an enclosed space within the chamber, the 120 bottom of said space being open.
